Specification for Design.

Patented Mar. 27, 1917.

Application filed October 30, 1916. Serial No. 128,623. Term of patent 14 years.

To all whom it may concern:

Be it known that I, MORTIMER C. FURCHGOTT, a citizen of the United States, residing at the city of St. Louis, State of Missouri, have invented a certain new, original, and ornamental Design for a Carton or other Article of Manufacture, of which the following is a specification, reference being had to the accompanying drawing, forming a part thereof, in which—

The figure is a perspective view of a carton embodying my new design.

My new design is applicable as a ruling or border not only for a carton, as shown in said drawing, but also for stationery, labels, and other articles of manufacture.

I claim:

The ornamental design for a carton or other article of manufacture, substantially as shown and described.

MORTIMER C. FURCHGOTT.
